NICHOLAS STRAUSSLER, OF LONDON, ENGLAND, ASSIGNOR TO BENDIX AVIATION CORPORATION, OF CHICAGO, ILLINOIS, A CORPORATION OF DELAWARE

CHARGE FORMING DEVICE

Application filed July 24, 1930. Serial No. 470,452.

This invention relates to charge forming devices, and more particularly to an improved carburetor adapted for use with explosive engines of the type used in aircraft 5 or automobiles.

Various means have heretofore been proposed for maintaining a constant fuel level in a carburetor. For the most part, such means are ineffective due to the inclination 10 or irregular movement of a vehicle upon which the carburetor is installed. Additionally, charge forming devices of the type heretofore used are inefficient, for the most part, during starting of the engine.

One of the objects of the present invention is to provide a novel carburetor which is so constructed as to overcome the above-mentioned difficulties.

Another object of this invention is to provide a carburetor including a novel combined valve and pump means so constituted that the supply of the fuel to the engine is controlled by suction.

Another object is to provide a novel carburetor of the floatless type which will function efficiently when the carburetor is shaken or suddenly brought to different positions by irregular movement of a vehicle upon which it is mounted.

Another object is to provide a carburetor having a carburizing chamber provided with novel means for varying the cross-sectional area of said chamber throughout a portion of the length of the latter.

A further object is to provide, in a carburetor having a Venturi-shaped carburizing chamber, novel flexible means for varying the cross-sectional area of the chamber, said means being particularly adapted to insure a proper mixture of fuel and air.

The above and other objects will appear more fully hereafter in the detailed description of the invention, one embodiment of which is illustrated in the accompanying drawing wherein like reference characters refer to like parts throughout the several views. It is to be expressly understood that the drawing is for the purposes of illustration only, and is not designed as a definition 5 of the limits of the invention, reference be-

ing had for this purpose to the appended claims.

In the drawing:

Fig. 1 is a sectional view of a carburetor embodying the invention taken along the line 1-1 of Fig. 2; and

Fig. 2 is a sectional view taken along the line 2-2 of Fig. 1.

In the form shown, 10 indicates the main body portion of a carburetor, fixed to the intake of an engine manifold having a vertical portion 11 and a horizontal portion 11^a, which is provided with a cylindrical opening 12 extending therethrough at right angles to the longitudinal axis thereof. The cylinder or chamber 12 is provided with a threaded closure 13 at its upper end as viewed in Fig. 2. The latter is formed with a central reduced portion 14 having an opening 15 therethrough for receiving a valve 16, the latter extending inwardly from the portion 14 and being provided with intersecting lateral and longitudinal passageways. The valve 16 is screw-threaded into the opening 15 and is accessible for adjustment by removal of plug 17. The inner wall of the opening 12 is provided with an annular flange 18 terminating in a bevel face 19 for receiving an annular disc 20 having a corresponding bevel face 21. Extending through the center of opening 12 is a tube 22 having its upper end screw-threaded into disc 20 as shown at 23. Tube 22 is provided with an enlarged portion 24 intermediate its ends constituting a collar having bevel faces 25 and orifices 26 connecting the bevel faces with the interior of the tube 22, the purpose of which will later be described.

Opposing pistons 27 are slidably mounted on the rod 22 within the cylindrical chamber constituted by opening 12 and are provided with bevel faces 28 for engagement with the faces 25 and orifices 26. Opposing coil springs 29 are disposed about the opposite ends of the tube 22 and are adapted to engage the adjacent piston 27 to yieldingly hold the faces 28 of the pistons in contact with the faces 25 whereby orifices 26 are closed. The lower end of chamber 12 is provided with an annular disc 31 having an

annular recess 32 for receiving the lower end of the lowermost spring 29 as viewed in Fig. 2. A coil spring 33 is positioned about the lower end of the tube 22 and coacts with the threaded closure 34 for the lower end of chamber 12 whereby said tube is maintained in proper position. The springs 29 are of such strength that the pistons are movable, under engine suction, against the tension of the springs. The pistons 27 divide cylinder or chamber 12 into two cylinders 35 and 36 which are subject to engine suction through openings 38 and 39 and suitable passageways 38^a and 39^a. By removing the threaded closure 34, easy access is had to the cylinder 12 for repairing or cleaning the tube 22, pistons 27 and springs 29. There is thus provided a simple and compact combination pump and valve structure that may be readily assembled or disassembled.

The upper end of chamber 12 is connected with a fuel supply lead (not shown) through an opening 41, formed in a boss 42 of the body portion 10, that leads to a fuel chamber 43 formed between the threaded closure 13 and disc 20. A suitable strainer 44 is disposed in the chamber 43. It will be noted that easy access is to be had to the strainer 44 for cleaning the same by removing closure 13.

The fuel enters the carburetor by way of the opening 41 through the strainer 44, the passageways in valve 16, and tube 22, but is prevented from further passage due to the engagement of pistons 27 with collar 24 until such time as operation of the engine is effective to produce the required suction within the intake to cause pistons 27 to move in opposite directions in chamber 12 whereby fuel is drawn into said chamber through the passageways in collar 24. A main fuel passageway 46 is provided for connecting the central portion of chamber 12 with the Venturi carburizing chamber 47 at the smallest cross-sectional area of the latter. Additional passageways 51 and 52, spaced apart and on opposite sides of the passage 46, may also be provided for supplying additional fuel to the carburizing chamber during high speeds of the engine.

The carburizing chamber 47 is provided with novel means for varying the cross-sectional area thereof, whereby maximum air speed in the chamber is secured in the plane of the fuel discharge orifice 46 and a more thorough mixing of the fuel and air is obtained. As shown, a flexible plate 53 is connected at its lower end to the chamber wall 54 by any suitable means such as screws 55 and at its upper end to a bell crank lever 56, the latter being rotatably mounted on a pin 57, which may be mounted on a wall of the chamber. Lever 56 is adapted to be operated by any suitable means such as a

rod (not shown) and is provided with a spring 58 interposed between a projection 59 on the body 10 and a projection 61 on lever 56 for counteracting the spring tension of the flexible plate 53. Upon actuation of the rocking lever 56 the flexible wall 53 may be moved to adjust the cross-sectional area of the chamber to any amount desired, and this without destroying the Venturi shape thereof.

An air orifice 62 is provided for connecting the fuel orifice 46 with the interior of the chamber 47 at a point above the orifice 46 whereby an emulsion of fuel and air is delivered to the carburizing chamber 47.

A throttle valve 64 is suitably positioned in chamber 47 between the fuel orifice 46 and the intake manifold 11, 11^a.

For supplying fuel to the engine manifold during the idling of such engine, an emulsion of air and gas is supplied through the passage 65 by way of the idling valve 66 and associated fuel orifices 67 and 68, the latter leading from the central portion of chamber 12. If desired, the outer wall 54 of the carburizing chamber 47 may be formed separately and fixed to the body 10 by means of bolts or screws 72 for rendering easy access to the flexible plate 53.

In operation, fuel is supplied to chamber 43 and the tube 22 by any suitable pressure means such as a pump, or by gravity, and upon starting the engine the suction in the cylinders is effective by way of the vacuum orifices 38 and 39, to cause the pistons 27 to move the same away from the openings in collar 24, whereupon suction in manifold 11, 11^a is effective through orifice 46 to draw fuel into the carburizing chamber 47. The lever 56 is actuated to reduce the cross-sectional area of passageway 47 to any desired amount at which time the suction from the engine cylinders will draw the fuel from the orifice 46 against the adjacent flexible wall, and by this impinging action of the fuel against the flexible wall the fuel is thoroughly commingled with the air as it is drawn into the engine intake. It will be noted that the velocity of the air in chamber 47 is greatest in the plane of orifice 46 whereby the entraining and mixing of the fuel is greatly facilitated.

Upon the starting of the engine, the lever 56 may be actuated to move the flexible plate 53 to any desired position in chamber 47 whereby the cross-sectional area of the latter is varied, and this without destroying the Venturi shape of said chamber. There is thus provided a flexible and adjustable venturi.

As the speed of the engine increases, the vacuum pull on the pistons 27 increases, whereby the latter are further separated to connect the central portion of the chamber 12 with the carburizing chamber 47 by

way of the diagonal passageways 51 and 52, so that additional fuel may be supplied for maintaining the engine at increased speed and power.

- 5 During starting, it will be seen that as the suction within the engine manifold is increased and decreased, the vacuum effect upon the pistons 27 will cause them to operate within chamber 12 and in so doing force 10 fuel through the passages 46, 51, and 52, whereby a rich mixture is obtained for priming the engine. It will also be readily apparent that upon stopping the engine the springs 26 will move the pistons to a closed 15 position and thereby prevent any leakage of the fuel through the orifices 26 and 46 and chamber 47. Furthermore, upon a sudden opening of the throttle valve the suction connections for actuating pistons 27 20 may be so disposed that the springs 29 are effective to move the pistons one toward the other, whereby an extra charge of fuel is forced from the passage 46 and the acceleration of the engine is expedited.
- 25 There is thus provided a carburetor embodying means for controlling the supply of fuel irrespective of the position of the carburetor and despite irregular motions or 30 jolts to which the carburetor may be subjected. Further, the novel yielding venturi operates in a superior manner to secure the desired mixtures for starting and normal 35 operation. The automatic means for supplying additional fuel at high engine speed increases engine flexibility. The yielding venturi operates to vary the cross-section of the chamber 47 adjacent the fuel inlet, whereby the fluid intake is brought into contact with the fuel inlet at its greatest 40 velocity. Also, the impinging action of the fuel against the flexible plate serves to more thoroughly atomize the fuel, thereby improving the engine operation and increasing 45 the power thereof.

50 While the present invention has been illustrated and described in connection with a down-draft carburetor, it will be obvious to those skilled in the art that the invention may readily be applied to any type of carburetor. Moreover, the flexible and 55 adjustable venturi may be used beneficially with other than floatless type carburetors. Other changes, modifications, substitutions, additions and omissions may be made in the structure without departing from the spirit and scope of the invention as defined in the appended claims.

What is claimed is:

- 60 1. In a carburetor, a carburizing chamber, a fuel orifice entering said chamber, a flexible member for varying the cross-sectional area of said chamber and having one end thereof secured to the wall of said chamber, 65 and manually operable means secured to

the other end of the member for adjusting the position of said member.

2. In a carburetor, a Venturi chamber, a fuel orifice entering said chamber, a flexible member for varying the cross-sectional area of said chamber and having one end thereof secured to the wall of said chamber, means comprising a bell-crank lever connected to the other end of the flexible member for moving said flexible member to maintain the Venturi shape of the chamber, and resilient means opposing said bell-crank lever for normally holding the flexible member in predetermined position.

3. In a charge forming device, a carburizing chamber, a power source, a fuel supply, and means including oppositely disposed pistons operative in opposite directions for connecting the fuel supply with the said chamber, the said means being adapted to be operated by the said power source.

4. In a carburetor for an internal combustion engine, a fuel chamber within said carburetor, suction operated pistons within said chamber and arranged to operate in opposite directions, a carburizing chamber, and means connecting the said fuel chamber with the said carburizing chamber, the last said means being under the control of the said pistons.

5. In a carburetor for supplying fuel to a hydrocarbon engine, a fuel supply, a fuel orifice, oppositely disposed pistons associated with said orifice and adapted to close said orifice when in one position and to open said orifice when in another position, and suction means associated with said carburetor for operating the said pistons.

6. In a carburetor for supplying fuel to an internal combustion engine, a fuel orifice, a Venturi intake opening, and means including a pair of pistons associated with the fuel orifice and adapted to be operated in opposite directions for supplying fuel to the said opening, the said means being responsive to the suction of the engine cylinders.

7. In a carburetor for an internal combustion engine, a carburizing chamber, and means for delivering fuel to said chamber, said means including a combined valve and pump means comprising a fuel orifice and a pair of pistons associated with said orifice and adapted to be operated in opposite directions.

8. In a carburetor for an internal combustion engine, a carburizing chamber, and means for delivering fuel to said chamber, said means including a combined valve and pump means comprising a fuel orifice and a pair of pistons operative in opposite directions adapted to be controlled by suction from the engine cylinders.

9. In a carburetor, an air chamber, a fuel chamber, means for connecting said chambers including a wall having a plurality of

- passageways therethrough, and means for selectively closing and opening the said passageways including a pair of pistons slidably disposed in the said fuel chamber and adapted to be automatically controlled. 70
10. In a carburetor, an air chamber, a fuel chamber, means for selectively connecting and disconnecting said chambers, the said means including a cylinder having a passageway through the wall thereof and a pair of oppositely slidable pistons mounted therein, and means for sliding the latter to close or open the said passageway. 75
11. In a charge forming device for a power source, a carburizing chamber, a fuel supply, means for connecting the fuel supply with said chamber including a cylinder having a plurality of passageways through the wall thereof and oppositely disposed pistons therein, yielding means tending to hold said pistons in abutting engagement, suction means connecting said cylinder with said power source, said pistons and said yielding means being adapted to be responsive to the suction of said power source. 80
12. In a charge forming device for a power source having a suction intake, a fuel chamber, suction operated pistons within said chamber, and means connecting the latter with said intake including an air inlet having a plurality of passageways in the wall thereof, flexible means within said inlet adapted to vary the cross-sectional areas thereof in the planes of said passageways, said connecting means being under control of said pistons. 85
13. In a charge forming device for a power source having a suction intake, a fuel chamber, suction operated pistons within said chamber, and means connecting the latter with said intake including an air inlet having a passageway in the wall thereof, flexible means within said inlet adapted to vary the cross-sectional area thereof in the plane of said passageway, the said flexible means adapted to maintain said air inlet of Venturi shape. 90
14. In a charge forming device for a power source having a suction intake, a fuel chamber, suction operated pistons within said chamber, and means connecting the latter with said intake including an air inlet of Venturi shape having a plurality of passageways in the walls thereof adjacent its smallest cross-sectional area, a flexible means within said inlet adapted to vary the cross-sectional areas thereof in the planes of said passageways without destroying the Venturi shape of said inlet. 95
15. In a charge forming device for a power source having a suction intake, a fuel chamber, suction operated pistons within said chamber, means connecting the latter with said intake including an air inlet of Venturi shape having a plurality of passageways therethrough, and means for selectively closing and opening the said passageways including a pair of pistons slidably disposed in the said fuel chamber and adapt- 100
- ways in the walls thereof adjacent its smallest cross-sectional area, and a flexible means within said inlet adapted to vary the cross-sectional areas thereof in the planes of said passageways without destroying the Venturi shape of said inlet, said connecting means being under control of said pistons. 105
16. In a carburetor for an internal combustion engine including a fuel cylinder having a tube therein, oppositely disposed pistons on said tube, yielding means tending to urge the pistons towards abutting engagements, and a single threaded means for rendering access to said tube, said pistons and said yielding means. 110
17. In a charge forming device comprising a casting having a cylinder therein, a fuel supply, means for connecting the fuel supply with said cylinder including a fuel chamber, a tube within said cylinder having an enlarged portion intermediate its ends, said enlarged portion being provided with bevel faces having orifices connecting said bevel faces with the interior of said tube, a valve connecting said fuel chamber with said tube, oppositely disposed pistons within said cylinder having corresponding bevel faces for engagement with the bevel faces on said enlarged portion, yielding means tending to urge the said corresponding bevel faces into contact relation, a carburizing chamber, a common wall between the said cylinder and said carburizing chamber having a plurality of passageways therethrough for connecting said cylinder with said carburizing chamber, suction means for operating said pistons, the said connecting means being under control of said suction means, and a flexible plate disposed in said carburizing chamber adapted to vary the cross-sectional areas of said carburizing chamber in the planes of said passageways. 115
18. In a charge forming device comprising a casting having a cylinder therein, a fuel supply, means for connecting the fuel supply with said cylinder including a fuel chamber, a tube within said cylinder having an enlarged portion intermediate its ends, said enlarged portion being provided with bevel faces and orifices connecting said bevel faces with the interior of said tube, a valve connecting said fuel chamber with said tube, oppositely disposed pistons within said cylinder having corresponding bevel faces for engagement with the bevel faces on said enlarged portion, yielding means tending to urge the said corresponding bevel faces into contact relation, a carburizing chamber, a common wall between the said cylinder and said carburizing chamber having a plurality of passageways therethrough for connecting said cylinder with said carburizing chamber, suction means for operating said pistons, the said connecting means being under control of said suction means, and a flexible 120
- 125
- 130

- plate disposed in said carburizing chamber adapted to vary the cross-sectional areas of said carburizing chamber in the planes of said passageways, said flexible plate adapted to form the carburizing chamber of Venturi shape.
19. In combination with a carburetor having a fuel chamber therein, of a carburizing chamber of Venturi shape having a passage in the plane of the smallest cross-sectional area thereof and connecting with the fuel chamber, and manually operated flexible means disposed in said carburizing chamber adapted to vary the cross-sectional area of the latter in the plane of said passageway.
20. In a carburetor, a carburizing chamber, a fuel supply means including a movable member operable to connect the fuel supply with the chamber, means for applying the suction of the chamber to the member for establishing a connection between the chamber and the fuel supply, and said movable member being arranged to pump fuel to the chamber when the suction therein is reduced.
21. In a carburetor, a carburizing chamber, a fuel supply means including a movable member operable to connect the fuel supply with the chamber, means for applying the suction of the chamber to the member for establishing a connection between the chamber and the fuel supply, said movable member being arranged to pump fuel to the chamber when the suction therein is reduced, and manual means for varying the chamber cross-section to control the suction applied to the member.
22. In a carburetor, a carburizing chamber, a fuel supply means including a movable member operable to connect the fuel supply with the chamber, means for applying the suction of the chamber to the member for establishing a connection between the chamber and the fuel supply, said movable member being arranged to pump fuel to the chamber when the suction therein is reduced, and a manually controlled flexible plate for varying the area of the chamber to control the suction applied to the member.
23. In a carburetor having a Venturi shaped air passage, a curved flexible member within said passage shaped to conform to and substantially fit against one wall of the passage, and manually operable means associated with the flexible member for moving it to vary the effective cross sectional area of the passage.

In testimony whereof I have signed this specification.

NICHOLAS STRAUSSLER.
